CANDACE WHEELER, OF NEW YORK, N. Y.

DESIGN FOR A CURTAIN FABRIC.

Design No. 17,229, dated March 29, 1887.

UNITED STATES PATENT OFFICE.

CANDACE WHEELER, OF NEW YORK, N. Y.

DESIGN FOR A CURTAIN FABRIC.

SPECIFICATION forming part of Design No. 17,229, dated March 29, 1887.

Application filed March 3, 1887. Serial No. 229,646. Term of patent 7 years.

To all whom it may concern:

Be it known that I, CANDACE WHEELER, a citizen of the United States, residing in the city, county, and State of New York, have invented and produced a new and original Design for Curtain and other Fabrics, of which the following is a specification, reference being made to the accompanying drawing, which shows a portion of a fabric containing my design.

My design consists in the conventionalized representation of the supporting-stalks, leaves, and flowers (the latter either wholly or partly opened) of the rose bush, as shown, respectively, at *a*, *b*, and *c*, the leaves *b* in the foreground being fully shaded, while a background is formed by the skeleton or unshaded representation, *e*, of the same kind of leaves. All these different parts are confused upon the en-

tire surface of the material thus ornamented, and at various points appears the conventionalized representations, *d*, of butterflies.

What I claim is—

1. The herein-described design for curtain and other fabrics, consisting in the representations of the stalks, leaves, and flowers of the rose-bush and the background of unshaded or skeleton leaves, substantially as shown. 25
2. The design herein described, consisting in the representation of the stalks, leaves, and flowers of the rose-bush, the background of skeleton leaves, and the butterflies, substantially as herein described and shown. 50

CANDACE WHEELER.

In presence of—

CHAS. HALL ADAMS,
CARRIE W. TROWBRIDGE.
